(57) **CLAIM**

The ornamental design for cellular telephone companion with display and keyboard, as shown and described.

DESCRIPTION

The cellular telephone companion with display and keyboard is intended for use as an attachment to a cellular telephone that has a limited input/output capability.

FIG. 1 is a perspective view of a cellular telephone companion with display and keyboard showing our new design in an open position;

FIG. 2 is a top plan view thereof;

FIG. 3 is a front elevation view thereof;

FIG. 4 is a right side elevation view thereof;

FIG. 5 is a rear elevation view thereof;

FIG. 6 is a left side elevation view thereof; and,

FIG. 7 is a bottom plan view thereof.

Broken lines shown in the drawings illustrate portions of the cellular telephone companion with display and keyboard and form no part of the claimed design.
